UNITED STATES PATENT OFFICE.

THIEBAUD LUTHRINGER, OF LYONS, FRANCE.

WATERPROOFING TISSUES.

SPECIFICATION forming part of Letters Patent No. 757,326, dated April 12, 1904.

Application filed April 25, 1903. Serial No. 154,309. (No specimens.)

To all whom it may concern:

Be it known that I, THIEBAUD LUTHRINGER, dyer, a citizen of the Republic of France, residing at 149 Rue Moncey, Lyons, in the Republic of France, have invented certain new Improvements in Waterproofing Tissues, of which the following is a specification.

This invention relates to a new process of waterproofing tissues composed of silk, wool, cotton, pure or mixed, by employing solid and inodorous carbids of hydrogen—such as stearin, paraffin, spermaceti, &c.—with sulfid of carbon as a dissolvent for these materials and its evaporation in the presence of gaseous carbonic acid.

To realize this new process of waterproofing, the tissues, which have been previously dressed by the ordinary means, must be passed into a vat A, holding a solution of sulfid of carbon containing one or more solid carbids of hydrogen, as explained above, then between rollers B, in view of expressing and returning to the vat the excess of the solution. At this time the tissue undergoes the action of the waterproofing. When passing out of the press or rollers, it is carried into a compartment or room D, where a fan running at great speed is placed directly below it and where is a current of gaseous carbonic acid emerging from a recipient F, placed underneath the fan. The power of this current will be regulated according to the nature of tissues to be treated. Above the tissue this compartment is shut up by a cover G, conducting the vapors of carbonic acid mixed with sulfid of carbon to a chimney, which mixture prevents and avoids all danger that can happen in the use of sulfid of carbon alone. When coming out of the present compartment, the tissue is waterproofed and dried and can be rolled directly around a roller J, worked by hand or mechanically at the speed required.

In order to completely remove all odor from the fabrics, the same may be made to pass, on emerging from the chamber D, into another chamber provided with a fan or ventilator and undergo an energetic ventilation, driving away all odor.

In passing the material between the rolls so that it can be inspected and to finally avoid the escape of odors of sulfid of carbon the compartment L, in which the vat A is placed,

may be shut up by a glass cover C, which can be raised and lowered at will. There is a door to this compartment through which the vat 55 containing the waterproofing solution is introduced.

What I claim as my invention, and desire to secure by Letters Patent, is—

1. A new process of waterproofing threads 60 and yarns for the weaving of textile fabrics such as silk, wool, cotton, pure or mixed, which consists in submerging the textile material in a solution of inodorous carbids of hydrogen solids such as stearin, paraffin, spermaceti, &c., dissolved in sulfid of carbon, and in leading said textile material through a closed chamber, and exposing it therein to a current of carbonic-acid gas, substantially as described.

2. A new process of waterproofing threads 70 and yarns for the weaving of textile fabrics such as silk, wool, cotton, pure or mixed, which consists in submerging the textile material in a solution of inodorous carbids of hydrogen solids such as stearin, paraffin spermaceti, &c., dissolved in sulfid of carbon and in leading said textile material through a closed chamber and exposing it therein to a current of carbonic-acid gas, said gas being projected 75 with force against the textile material by suitable ventilating means, substantially as described.

3. A new process of waterproofing threads 80 and yarns for the weaving of textile fabrics such as silk, wool, cotton, pure or mixed which consists in submerging the textile material in a solution of inodorous carbids of hydrogen solids such as stearin, paraffin spermaceti, &c., dissolved in sulfid of carbon, then 85 removing the excess of solution from the textile material by pressure, and in leading said textile material through a closed chamber exposing it therein to a current of carbonic gas said gas being projected with force against 90 the textile material by suitable ventilating means.

In testimony whereof I have hereunto set my hand, in presence of two subscribing witnesses, this 11th day of April, 1903.

THIEBAUD LUTHRINGER.
